UNITED STATES PATENT OFFICE.

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

LIGHT SIGNAL.

Application filed August 11, 1923. Serial No. 656,844.

My invention relates to light signals.

I will describe two forms of light signals embodying my invention, and will then point out the novel features thereof in 5 claims.

In the accompanying drawings, Fig. 1 is a vertical sectional view showing one form of light signal embodying my invention. Fig. 2 is a view showing in front elevation, 10 the signal shown in Fig. 1. Fig. 3 is a sectional view on the line III—III of Fig. 1. Fig. 4 is a sectional view along the line IV—IV of Fig. 1. Fig. 5 is a fragmental view 15 showing a modification of the light deflector shown in Fig. 1 and also embodying my invention. Fig. 6 is a sectional view on the line VI—VI of Fig. 1. Fig. 7 is a view showing in elevation, on a greatly reduced scale, the signal of Fig. 2 with the front 20 plate E and the casting F removed.

Similar reference characters refer to similar parts in each of the several views.

Referring first to Figs. 1 and 2, the signal comprises a casing A of cast iron or other 25 suitable material having a front plate E which is provided with three pairs of holes T through which the signal indications are displayed. The two holes T of each pair are on opposite sides of the center of the 30 signal. Supported by the front plate E and in substantially the same plane therewith is a plate B of sheet metal or other suitable material which is preferably painted black, and one function of which is to provide a 35 uniform background for the signal indications and thus increase the range of visibility of the signal. Two of the holes T^x are disposed vertically, one above the other and are each provided with a cover glass 1^x. 40 Two other holes T^r are disposed horizontally and provided with cover glass 1^r. The two remaining holes T^y are so arranged that a line connecting their centers makes an angle 45 of 45° with the vertical and the horizontal and are provided with cover glasses 1^y. A casting F is pivotally mounted in the center of the casing A, and contains a source 50 of light such as an incandescent lamp G. Supported by the casting F and located on either side of the lamp G are two oppositely disposed lens structures as here shown each comprising two lenses 4 and 5. As indicated in Fig. 1, these lenses are so designed and

so disposed that light emanating from the lamp G is projected in two oppositely disposed beams of parallel rays along the arrows X. Associated with each of the holes T in the front plate E is a light deflector designated by the reference character 9 with a suitable exponent and arranged to 55 redirect light incident thereupon from the lamp G, through the associated cover glass 1 (see Fig. 7). As here shown, each deflector is a silvered mirror, which mirror is supported adjustably from the casing A by 60 a threaded stem 10 and lock nuts 10^a.

As shown in Fig. 1, the casting F is in such position that the projected beams of light are directed vertically upward and downward in the directions indicated by 70 the arrows X, X. Interposed in each of these beams is one of the light deflectors 9^x. The angular disposition of these deflectors is such that the beams of light incident upon them along arrows X are redirected through 75 the two cover glasses 1^x in spaced paths, substantially parallel, as indicated by the arrows S.

The signal is mounted in such a position that the arrows S point toward the point or 80 points from which the signal indications are to be observed.

An alternative form of light deflector is shown in Fig. 5 wherein the deflector comprises a back plate 11 provided with a 85 plurality of transversely extending prisms 12 by means of which the light is refracted through the cover glass 1.

It is understood that other light deflectors similar in all respects to those provided for 90 cover glasses 1^x are associated with the remaining cover glasses 1^y and 1^r. Means are also provided, as will appear hereinafter, for rotating the casting F, thereby directing the beams of light from the lamp G 95 through any desired pair of cover glasses. As a result, the appearance of the signal as viewed from the front is two spaced horizontal beams of light, the line joining these beams being disposed vertically, horizontally, or inclined 45°, depending upon the position of the casting F, as will be plain from Figs. 1 and 2.

I also provide means for distinctively 100 coloring the beams of light issuing from each pair of cover glasses. This may be

accomplished by making the light deflectors 9 of distinctive colors. For example, the deflectors associated with cover glasses 1^g and shown in Fig. 1 may be of green glass, the deflectors associated with cover glasses 1^g may be of yellow glass, whereas those associated with cover glass 1^r may be of red glass. These colors are in accordance with standard railway signaling practice and correspond to signal indications of proceed, caution and stop, respectively. It will be clear that these indications comprise both color and position signaling, which feature is an advantage because it permits the indication to be correctly read by persons partially or completely color blind.

As shown in the drawing the casting F is in such position that light is projected from lamp G through cover glasses 1^g, thus displaying a proceed indication. In order to project light from lamp G through cover glasses 1^r this casting F must be rotated through 45 angular degrees in clockwise direction as the signal is viewed in Fig. 2. Similarly, to project light through cover glasses 1^g this casting must be rotated 90° in clockwise direction as the signal is viewed in Fig. 1.

The casting may be moved to the operative position with respect to any desired pair of cover glasses by means of a shaft H which is rigidly attached to this casting. This shaft is journalled in a suitable bearing in a plate 40 which forms the back wall of the casing A and the front wall of a mechanism box C which contains the operating mechanism for rotating shaft H and thus moving casting F to the desired position.

Referring now to Fig. 3, a pinion 13 is rigidly attached to the shaft H. Two electro magnets 20 and 20^a are rigidly supported by the plate 40, and associated with each such magnet is a segmental gear arranged to mesh with the pinion 13. Segmental gear 14 associated with magnet 20 is pivotally supported at point 42, while segmental gear 14^a associated with magnet 20^a is pivotally supported at point 41. Pivoted also at point 41 is a member 16 having an armature 15^a adapted to be operated by magnet 20^a and a lip 44 for engaging the lower side of the arm which carries segmental gear 14^a. Downward motion of this member is limited by a screw stop 19. The arm carrying segmental gear 14 is provided on its lower edge with an armature 15 arranged to be attracted by magnet 20. A biasing member 1 is also pivotally supported at point 42 and is provided with a weight 18 and a lip 46 for engaging the lower side of the arm carrying segmental gear 14. The force of gravity on this weight normally tends to force the weight 18 downwards until it abuts against stop screw 19, thus causing lip 46 to engage

segmental gear 14 and bias the moving parts 65 of the entire system to the positions shown in this drawing, in which the parts are in the positions corresponding to a stop indication.

The energization of the magnets 20 and 20^a is controlled by a relay designated as a whole by the reference character R and comprising two windings 21 and 22 and a rotor element 23. This rotor element 23 controls a movable contact finger 24 in the usual and well known manner. The energization of windings 21 and 22 may be accomplished in any convenient manner, as is well understood by those skilled in the art. Magnet 20 is provided with a circuit which passes from a source of energy, as a battery K, through wire 27, left hand contact 24-26 of relay R, wire 28, winding of magnet 20, and wires 29 and 30 back to battery K. Magnet 20 is provided with a circuit which passes from battery K, through wire 27, right hand contact 24-25 of relay R, wire 31, winding of magnet 20, and wires 32 and 30 back to battery K.

The operation of the apparatus is as follows: As hereinbefore stated, the parts of the mechanism as shown in Fig. 3 are in the positions corresponding to a stop indication. If the relay R is energized in such direction as to close contact 24-26, magnet 20^a becomes energized, thus causing armature 15^a to move upwards. This motion causes lip 44 to engage segmental gear 14^a which gear thereupon moves in a counter-clockwise direction about its pivot 41. It is clear that this motion is transmitted through pinion 13 to shaft H and segment gear 14 causing gear 14 to rotate in a clockwise direction against the bias exerted by weight 18 until armature 15^a abuts against the pole face of magnet 20^a. During this operation armature 15 completes one half of its total motion toward the pole face of magnet 20. In the position which the parts will then occupy the shaft H has been rotated 45 degrees and the signal will display a caution indication.

If relay R is now energized in such direction as to close contact 24-25, magnet 20 is energized, thus drawing armature 15 downwards until it engages the pole face of magnet 20 in which position the casting F is in such position that the signal displays a proceed indication. Since further upward motion of member 16 is prevented by engagement of armature 15^a with the pole face of magnet 20^a, segment gear 14^a, during motion of shaft H from the caution to the proceed position, simply rotates about its pivot 41, moving out of engagement with lip 44 without affecting the position of members 16.

Although in the present application I have shown a mechanism involving magnets and segmental gears for operating the casting F,

I do not desire to limit myself to a mechanism of this character, it being understood that the casting F may be operated by a mechanism of any other suitable type such as for example as the Z armature type or the motor type.

In order to prevent "phantom indications", that is, false indications due to reflected sunlight, I equip casting F with shields 34 which prevents light, entering the casing from the exterior through one of the cover glasses, from being reflected within the signal and issuing from the opposite cover glass and thus displaying an improper indication. These shields are best shown in Figs. 1 and 6. For example, if the signal is displaying a stop indication, and sunlight or any other foreign light enters the signal at upper cover glass 1, this light is deflected toward the center of the signal, but it is obstructed by the shields 34 and hence is not allowed to be projected from the lower cover glass 1 by deflector 9. There is therefore no possibility of "phantom indication".

Under some conditions of operation, it is desirable to permit an observer stationed at a point in rear of the signal, as on a train which has passed the signal moving in the direction in which the signal governs, to ascertain whether or not the signal is displaying a stop indication. To accomplish this result I provided a hole in the back wall D of the mechanism box C. As best shown in Fig. 1, this hole is provided with a cover glass 35 which is protected from snow and direct rays of the sun by means of a hood 36. An auxiliary light source is provided within the mechanism box, which source as here illustrated is a small incandescent lamp 6. Interposed between the lamp 6 and the cover glass 35 is a small semaphore spectacle 7 as best shown in Fig. 4. This spectacle is provided with a transparent roundel 8 and is rigidly attached to shaft H and rotates therewith. The parts are so disposed that this transparent roundel is interposed between the lamp 6 and the cover glass 35 only when the signal is displaying a stop indication. The main signal lamp G is constantly energized from a suitable source not shown in the drawing, and the auxiliary lamp 6 is connected in series therewith. Positive indication is therefore given to the rear when a stop indication is displayed by the signal.

Although I have herein shown and described only one form of light signal and one modification thereof embodying my invention, it is understood that various changes and modifications may be made

therein, within the scope of the appended claims without departing from the spirit and scope of my invention.

Having thus described my invention, what I claim is:

1. A signal comprising a suitable casing, two pairs of apertures in said casing so disposed that the line through the centers of the apertures of one pair intersects the line through the centers of the apertures of the other pair, a light source, a light deflecting device for each aperture for redirecting therethrough light incident upon such device from said source, the beams projected by said devices being all in parallel relation, and means for selectively projecting light from said source onto the devices associated with either said pair of apertures. 75

2. A signal comprising a suitable casing, two pairs of apertures in said casing so disposed that the line through the centers of the apertures of one pair intersects the line through the centers of the apertures of the other pair, a light source, a light deflecting device for each aperture for redirecting therethrough into paths substantially parallel light incident upon such device from said source, and means for selectively projecting light from said source onto the devices associated with either said pair of apertures. 85

3. In combination, a light source, means for projecting two oppositely directed beams of light from said source, a pair of similarly colored light deflectors for redirecting said beams into parallel paths, a second pair of deflectors of a color different from said first pair all of said deflectors being confined between two parallel planes, and means for rotating said first means into operative position with respect to said second pair of deflectors. 95

4. A signal comprising a front plate having a first pair of apertures disposed on a vertical line, a second pair of apertures disposed on a horizontal line, and a third pair of apertures disposed on a line inclined at 45 angular degrees with the vertical, a light source, a colored deflecting means associated with each pair of apertures for redirecting light incident thereupon from said source through the associated apertures and simultaneously giving said light a distinctive color, collimating means associated with said source, and means for selectively moving said collimating means into a position in which light is projected from said source to the deflecting means associated with any pair of apertures. 110

In testimony whereof I affix my signature.
CLARENCE S. SNAVELY.

CERTIFICATE OF CORRECTION.

Patent No. 1,657,232.

Granted January 24, 1928, to

CLARENCE S. SNAVELY.

It is hereby certified that error appears in the printed specification of the above numbered patent requiring correction as follows: Page 3, line 99, claim 3, after the word "pair" insert the words "and disposed in a line which intersects the line through the deflectors of said first pair"; and that the said Letters Patent should be read with this correction therein that the same may conform to the record of the case in the Patent Office.

Signed and sealed this 14th day of February, A. D. 1928.

M. J. Moore,
Acting Commissioner of Patents.

Seal.
